WINDOW FRAME

Allan Landsman, 506 W. 113th St.,
New York, N.Y. 10025

Filed Aug. 12, 1966, Ser. No. 3,459

Term of patent 14 years

(Cl. D13—1)

FIG. 1

FIG. 2

FIG. 3

FIG. 4

FIG. 1 is a top plan view of a window frame embodying my new design;

FIG. 2 is a front elevational view of the new design;

FIG. 3 is a side elevational view, partially in section, with the frame removed, at least in part; and

FIG. 4 is a bottom elevational view of the new design.

I claim:

The ornamental design for a window frame, as shown.
